KEY ACTUATABLE LOCK

Charles S. Gehrie, Mendham, N. J., assignor to Presto Lock Company, Garfield, N. J., a limited partnership consisting of Abraham Levine, Mendham, N. J., a general partner; Mack Povill, New York, N. Y., a general partner; and A. Loeb Salkin, New York, N. Y., a limited partner

Application January 21, 1953, Serial No. 332,266

8 Claims. (Cl. 70—71)

This invention relates to an improved key actuatable lock for use in releasably securing together separable parts, such e. g. as the body and cover of a container, suitcase or the like.

The invention has for an object to provide a novel lock structure of the type having pivotally supported, oscillatable bolt members which are adapted to be moved into and out of engagement with a slotted keeper plate, the movements of said bolt members being induced by a slide plate that is controlled by rotatable cam means adapted to be actuated by engagement of a key therewith; the lock structure including a novel housing assembly to contain said bolt members, slide plate and cam means; the lock structure further including a cylinder to rotatably support a key barrel, and retention clip means for retaining said cylinder in operative assembled relation to the housing assembly, said cam, and to the body of a container or the like to be served by the lock.

The invention has for another object to provide a cylinder and key barrel assembly, wherein the key barrel is removable subject to interchange for correspondence to a selected one of a variety of key shapes; said assembly including means adapted to releasably hold a selected key barrel in the cylinder.

The above and other objects will be understood from a reading of the following detailed description of this invention in connection with the accompanying drawings, in which:

Fig. 1 is a fragmentary plan view of separable parts of a container or the like, showing the lock mechanism of this invention operatively applied thereto; and Fig. 2 is a sectional view of said separable parts of the container or the like, showing the applied lock mechanism in side elevation.

Fig. 3 is a longitudinal vertical sectional view, taken on line 3—3 in Fig. 1, but drawn on an enlarged scale, and showing an actuating key engaged in said lock mechanism and operated to lock the latter.

Fig. 4 is a horizontal sectional view, taken on line 4—4 of Fig. 3, showing the bolt members of the lock mechanism in keeper plate engaging position; and Fig. 5 is a view, similar to that of Fig. 4, but showing the bolt members of the lock mechanism in released relation to the keeper plate.

Fig. 6 is a horizontal sectional view, taken on line 6—6 in Fig. 3; and Fig. 7 is a fragmentary vertical sectional view, taken on line 7—7 in Fig. 6.

Similar characters of reference are employed in the above described views, to indicate corresponding parts.

Referring to the drawings, the reference character 10 indicates one of the separable parts, e. g. a container body, and 11 the other separable part, e. g. a container cover, to which the lock mechanism of this invention is applied. As shown, the key actuatable mechanism of the lock is affixed to the body part 10, and the keeper plate which is releasably engageable thereby is affixed to the cover part 11.

The key actuatable mechanism of the lock comprises a

2

frame member 12 having side walls 13, a forward end wall 14 and a rearward end wall 15 upstanding therefrom. The forward end wall 14 and adjacent ends of the side walls 13 are cut away to provide lateral openings 16 leading outwardly from the respective sides of the frame member 12 at the forward end portion thereof. Struck up from the respective side marginal portions of frame plate 12, to upstand therefrom in rearwardly spaced relation to the forward end thereof, are transverse fulcrum posts 17.

A pair of bolt members 18 are supported upon the frame member 12, respectively adjacent opposite sides of the forward end portion thereof. Each bolt member 18 is provided at its forward free end portion with a laterally and outwardly projecting bolt nosing 19, and with a laterally and inwardly projecting heel portion 20. Each bolt member 18 is provided, in the outer side margin of its rear end portion, with an indenting notch 21 which straddles and embraces the inner edge of a fulcrum post 17, whereby said bolt members are pivotally supported upon the frame member 12 for lateral swinging movements by which their bolt nosings 19 are projected outwardly through the side openings 16 of the frame member or inwardly withdrawn through the latter. Each bolt member is further provided, at its rear end portion, with a laterally and inwardly projecting tail piece 22.

Longitudinally slidably upon the frame member 12, between its side walls 13, is a slide plate 23 which is provided with a transverse opening 24 adapted to receive, 30 and its forward and rear edges to be engaged by, a rotatable eccentric cam means, as hereinafter described. Integral with and projecting forwardly from said slide plate 23 is a central longitudinal arm 25 which terminates, at its forward end, in a laterally enlarged thrust 35 head 26 which is disposed between the bolt members 18 for operative engagement therewith. The rearward end of said thrust head 26 is formed to provide oppositely extending transverse retractor shoulders 27.

The cam means by which the slide plate is engaged 40 comprises an upstanding hub 28. Connected with this hub 28, in eccentric relation to the axis thereof, is a cam member 29 which is disposed within the opening 24 of the slide plate 23 between the forward and rear edges of said opening. The major axis of the eccentric cam member 29, in the respective positions of rest of said cam member, is aligned with the central longitudinal axis of the slide plate 23. Projecting from the underside of the cam member 29, in axial alignment with the hub 28, is a hub extension 30 which extends downwardly through an opening with which the frame member 12 is provided. Said opening comprises a section 31 of minor radius, corresponding to the radius of the hub extension 30, and a section 32 of major radius, whereby to form, in connection with said opening diametrically opposite stop shoulders 33 and 33' intermediate said sections. Projecting radially from the hub extension 30, to move in the major section 32 of said opening, is a stop lug 34 which, by engagement with one or the other of said stop shoulders, determines respective positions of rest of the cam member 29. Formed in the upper end of the hub 28 is an upwardly open transverse slot 35, which is adapted to be operatively engaged by an actuating key by which the lock is operated, as will be hereinafter more particularly described. This slot 35 is disposed parallel to the major axis of the cam member 29. Supported by and across upstanding walls of the frame member 12 is a bearing plate 36, which is provided with a bearing portion 37 in which the hub 28 of the cam means is journaled. The side walls of the frame member 12 are preferably provided with suitably disposed, upwardly projecting positioning lugs 38 which engage in correspondingly notched marginal portions of the bearing plate 36, whereby to hold the lat-

ter against displacement from its assembled relation to said frame member. The bearing plate 36 is also provided at its opposite end with upstanding spacer tongues 39, to predetermine the overlying spaced relation thereto of a top housing plate.

The housing assembly by which the lock mechanism is supported comprises a top housing plate having a main body part 40 which is provided with a rearward extension 41, preferably of reduced width, extending in the plane thereof. The body part 40 of the top housing plate bridges over the spacer tongues 39 of the bearing plate 36, so as to lie in a plane parallel to but spaced above said bearing plate, thus providing intermediate space into which the upper end of the cam member hub 28 extends. Downwardly offset from the forward end of the main body part 40 of the top housing plate, by a dependent angular portion 42, is a forwardly extending cover section 43 which overlies the forward portion of the frame member 12 and its contained bolt members 18. Said cover section 43 is folded, at 44, about the forward end of the frame member 12 to form a doubled back section 45 which underlies and supports the forward end portion of said frame member 12. Underlying and supporting the rearward end portion of the frame member 12 is a bottom housing plate 46. Upwardly offset from the rearward end of the bottom housing plate 46, by an upstanding angular portion 47, is a rearward extension 48 which underlies the rearward extension 41 of the top housing plate. The forward end portion of the bottom housing plate 46 overlaps the underside of the free end portion of the doubled back section 45 of the top housing plate. Extending laterally respectively from opposite sides of the forward end portion of the bottom housing plate 46 are clenching tongues 49, which are turned upwardly across the sides of the frame member 12, and then clenched over the cover section 43 of the top housing plate, thus interlocking the housing plates together in their assembled enclosing and supporting relation to the frame member 12 and the lock mechanism parts contained therein.

In mounting the lock mechanism in operative relation to a container or the like to be served thereby, the assembly is applied to the underside of the wall of the container body 10 adjacent to the edge thereof to which the edge of the container cover 11 is opposed, and in such position that the bolt member containing forward end portion of the assembly projects outwardly beyond the edge of the container body 10, whereby, when the container cover 11 is closed upon said container body, it can pass through the opening of a keeper plate 50 which is affixed, by screws, rivets or the like 51, to the container cover 11, to depend from the underside of the latter in opposition to said assembly. When the assembly is thus arranged, it is held in place by a fastening screw, rivet or the like 52 which is engaged through the superposed top and bottom housing plate extensions 41 and 48, and the container body 10.

The assembly being in place is ready to have assembled therewith and with the container body 10 a key barrel supporting cylinder. Provided in the body part 40 of the top housing plate is an opening 53, which is disposed in axially aligned relation to the cam member hub 28. Extending radially inward from the margin of said opening 53 is a key tongue 54. Provided in the wall of the container body 10 is a through opening 55, which corresponds to and is aligned with the opening 53 of the top housing plate body part 40.

The key barrel supporting cylinder comprises a cylindrical body 56 having a downwardly open chamber or bore 57 which is closed at its upper or outer end by a top wall 58. Said top wall 58 is formed to provide an external annular flange 59. Formed in said top wall 58 is an opening 60 leading outwardly from the chamber or bore 57 of the cylinder body, thus providing an internal annular stop shoulder 61. Rotatably mounted within the chamber or bore 57 of the cylinder body is a hollow

key barrel 62, the upper end of which is stopped against the stop shoulder 61. Said key barrel is closed at its upper end by an extension 63 of reduced diameter, which projects exteriorly through said top opening 60 of the cylinder body. Means to retain the key barrel within the cylinder body, in operative relation thereto, comprises a keeper washer 64. This keeper washer is provided with supporting legs 65 respectively dependent from its margins at diametrically opposite sides thereof. These supporting legs 65 are received in perpendicular grooves or channels 66 which indent the internal wall surfaces of the chamber or bore of the cylinder body, and which extend to the lower end of the latter, whereby not only to retain the keeper washer against downward displacement from its operative key barrel supporting position, but also against rotative displacement from a required predetermined position within the cylinder body. Indenting the external wall surface of the cylinder body 56 is a perpendicular groove or channel 67, which opens endwise from the lower or bottom end of the cylinder body.

To assemble the key barrel supporting cylinder in connection with the wall of the container body 10, and in operative relation to the lock mechanism assembly, the cylinder body 56 is inserted downwardly through the opening 55 in the container body wall, and thence through the opening 53 in the body part 40 of the top housing plate, until its annular top end flange 59 abuts the outer face of said container body wall. When thus arranged, the open lower or bottom end of the cylinder body 56 projects into the space between the bearing plate 36 and the body part 40 of the top housing plate, so that the cam member hub 28 is entered within the lower end of the chamber or bore 57 of the cylinder body in axially aligned relation to the key barrel 62 supported by said cylinder body. When so assembling the cylinder, its external channel or groove 67 is aligned with and so as to receive the key tongue 54 of the body part 40 of the top housing plate, thus interlocking the cylinder with the latter against rotative displacement from its operative assembled relation to the lock mechanism assembly. Means is provided to secure the cylinder against outward axial displacement from the lock mechanism assembly and from the container body wall, while at the same time serving, together with the fastening screw, rivet or the like 52, to secure the lock mechanism assembly to the container body 10. This means comprises a pronged spring clip element 68, the prongs 69 of which are adapted to straddle the cylinder body 56. The external wall surfaces of the inner end portion of the cylinder body are provided, respectively at opposite sides of said cylinder body, with transverse channels or grooves 70, which extend adjacent to and parallel with the underface of the body part 40 of the top housing plate. When the cylinder is disposed in place, as above described, the clip element 68 is inserted laterally through the open space between the bearing plate 36 and the body part 40 of the top housing plate, whereby to engage the cylinder straddling prongs 69 thereof through said channels or grooves 70 and beneath and in engagement with the underface of said body part 40 of the top housing plate, thus strongly interlocking the cylinder with the lock mechanism housing assembly and with the wall of the container body 10.

The keeper washer 64 is provided with a slotted key passage opening 71 which is aligned with and opposed to the key reception slot 35 of the cam member hub 28, and which is maintained against displacement from such aligned relation thereto by reason of the predetermined interengaged relation of said keeper washer and cylinder body, and by reason of the fact that the cylinder body is held against rotative shift or movement by the engagement in its channel or groove 67 of the key tongue 54 of the body part 40 of the top housing plate.

The exteriorly projecting extension 63 of the key barrel is longitudinally pierced to provide a key admission opening 72 of a cross sectional shape corresponding to the

cross sectional shape of a selected key 73 by which the lock mechanism is to be actuated. Key barrels respectively provided with variously shaped key admission openings 72 corresponding to various key shapes can be interchangeably assembled with the cylinder, whereby to condition the lock mechanism for actuation only by a given selected key.

The container cover 11 being closed relative to the container body 10, so that the forwardly projecting end portion of the lock mechanism assembly enters through the aperture of the slotted keeper plate 50, to actuate the lock mechanism, the key 73 is inserted through the key barrel 62-63 and keeper washer 64 so that its extremity enters the slot 35 of the cam member hub 28. The entered key is turned clockwise, whereby to rotate the cam 29 against the forward edge of the slide plate opening 24, thus moving the slide plate forward so as to push the thrust head 26 against the heel portions 20 of the bolt members 18, and thereby to swing outward the bolt members 18 so as to project the nosings 19 thereof behind and in holding engagement with the keeper plate 50 (see Figs. 1 to 4 inclusive). To release the lock mechanism, the inserted key 73 is turned counterclockwise, whereby to rotate the cam 29 against the rearward edge of the slide plate opening 24, thereby retracting the slide plate 23 and thrust head 26, so that the shoulders 27 of the latter drag against the tail pieces 22 of the bolt members 18, thus swinging the latter inwardly to withdraw their nosings 19 from engaged relation to the keeper plate 50, whereupon the container cover 11 can be opened relative to the container body 10.

Having now described my invention, I claim:

1. In a key actuatable lock for releasably locking together separable parts, a slotted keeper plate adapted to be mounted on a wall of one said part, a lock mechanism to engage said keeper plate, a housing to support said lock mechanism, the lock mechanism housing assembly being adapted to be mounted on a wall of the other said part in such relation thereto that a freely projecting forward end portion of said assembly is engageable through said keeper plate when said parts are closed together; said lock mechanism comprising a frame member, pivoted bolt members supported by said frame member and adapted to be laterally projected from opposite sides of the forward end portion thereof for locking engagement with said keeper plate, a slide plate mounted on said frame member having means for oscillating said bolt members, a rotatable cam member for actuating said slide plate, said cam member having an upstanding key engageable hub, a bearing plate for said hub, said bearing plate being supported by said frame member in overlying relation to the cam member; the housing for said lock mechanisms comprising a top housing plate, a bottom housing plate, and means for securing said housing plates together in their housing relation to the lock mechanism; a cylinder adapted to extend through the wall of the part upon which the lock mechanism housing assembly is to be mounted and through the top housing plate in axially aligned opposition to the key engageable hub of the cam member, a key barrel rotatably mounted in said cylinder through which an actuating key can be passed into operative engagement with said cam member hub, and means to releasably interlock said cylinder in affixed relation to the top housing plate.

2. In a key actuatable lock according to claim 1, a removable keeper washer within the cylinder to retain the key barrel in operative assembled relation to the latter, and means to hold said keeper washer in a predetermined assembled relation to the cylinder, said keeper washer having a key passage opening therethrough.

3. In a key actuatable lock according to claim 1, where-in the means to releasably interlock the cylinder in affixed relation to the top housing plate comprises a pronged spring clip inserted laterally into the lock mechanism housing assembly beneath and in engagement with the

top housing plate and with its prongs straddling the cylinder body, and said cylinder body having transverse grooves in its opposite sides through which the clip prongs extend.

5 4. In a key actuatable lock according to claim 1,
wherein the means to releasably interlock the cylinder in
affixed relation to the top housing plate comprises a
pronged spring clip inserted laterally into the lock mech-
anism housing assembly beneath and in engagement with
10 the top housing plate and with its prongs straddling the
cylinder, said cylinder body having transverse grooves
in its opposite sides through which the clip prongs ex-
tend, and said cylinder body and said top housing plate
having cooperative means to prevent rotative displace-
15 ment of the former.

5. In a key actuatable lock according to claim 1, wherein the means to releasably interlock the cylinder in affixed relation to the top housing plate comprises a pronged spring clip inserted laterally into the lock mechanism housing assembly beneath and in engagement with the top housing plate and with its prongs straddling the cylinder body, said cylinder body having transverse grooves in its opposite sides through which the clip prongs extend, said cylinder body and said top housing plate having cooperative means to prevent rotative displacement of the cylinder, a removable keeper washer within the cylinder to retain the key barrel in operative assembled relation to the latter, and means to hold said keeper washer in predetermined assembled position in the cylinder, said keeper washer having a key passage opening therethrough.

6. In a key actuatable lock for releasably locking together separable parts, a slotted keeper plate adapted to be mounted on a wall of one said part, a lock mechanism to engage said keeper plate, a housing to support said lock mechanism, the lock mechanism housing assembly being adapted to be mounted on a wall of the other said part in such relation thereto that a freely projecting forward end portion of said assembly is engageable through 35 said keeper plate when said parts are close together; said lock mechanism comprising a frame member, pivoted bolt members supported by said frame member and adapted to be laterally projected from opposite sides of the forward end thereof for locking engagement with said 40 keeper plate, a slide plate mounted on said frame member having means for oscillating said bolt members, a rotatable cam member for actuating said slide plate, said cam member having an upstanding key engageable hub portion, a bearing plate for said hub portion, said bearing 45 plate being supported by the frame member in overlying relation to the cam member; the housing for said lock mechanism comprising a top housing plate having a body part overlying said bearing plate in spaced relation thereto and a downwardly offset cover section overlying the 50 forward end portion of the frame member and the bolt members contained therein, said cover section having a doubled back end portion to underlie the forward end portion of the frame member, a bottom housing plate, and means for securing said housing plates together in 55 their housing relation to the lock mechanism; a cylinder extending downwardly through the wall of the part upon which the lock mechanism housing assembly is mounted and through the body part of the top housing plate in 60 axially aligned relation to the key engageable hub of the cam member, a key barrel rotatably mounted in said cylinder through which an actuating key can be passed into operative engagement with said cam member hub, and means to releasably interlock said cylinder in fixed 65 relation to the body part of the top housing plate of the lock mechanism housing assembly.

7. In a key actuatable lock according to claim 6, where-
in the means to releasably interlock the cylinder with
the top housing plate comprises a
pronged spring clip inserted laterally into the lock mech-
anism housing assembly beneath and in engagement with

the top housing plate and with its prongs straddling the cylinder body, said cylinder body having transverse grooves in its opposite sides through which the clip prongs extend, and said cylinder body and said top housing plate having cooperative means to prevent rotative displacement of the former.

8. In a key actuatable lock according to claim 7, including a removable keeper washer within the cylinder to retain the key barrel in operative assembled relation to the latter, and means to hold said keeper washer in predetermined assembled position in the cylinder, said keeper washer having a key passage opening therethrough.
